UNITED STATES PATENT OFFICE.

JAMES P. MCKINNEY, OF PITTSBURGH, PENNSYLVANIA.

HINGE.

1,097,458.

Specification of Letters Patent.

Patented May 19, 1914.

Application filed August 26, 1911. Serial No. 646,242.

To all whom it may concern:

Be it known that I, JAMES P. MCKINNEY, a citizen of the United States, and resident of Pittsburgh, in the county of Allegheny and State of Pennsylvania, have invented a new and useful Improvement in Hinges; and I do hereby declare the following to be a full, clear, and exact description thereof.

My invention relates to steel hinges, and 10 its object is to provide a light weight pressed steel hinge in which there shall be a full bearing of the body of the metal of the knuckles forming the barrel upon each other and upon the pintle, and the hinge itself 15 shall be properly stiffened both in the knuckle portions and in the body of the hinge to carry the load, and shall have a full bearing upon the surface of the door or other part to which the hinge is connected.

20 To these ends the invention comprises a pressed steel hinge having its body raised or pressed upwardly from its back face at the knuckle so as to form part of the knuckle which is bent to cylindrical form thus forming 25 a cylindrical knuckle of the same diameter throughout and including therein the bent portion of the body.

It also consists in providing the knuckle 30 with seats fitting on both sides of such raised portion of the body of the hinge said knuckle having lugs fitting in said seats to lock and support the knuckle while giving it the cylindrical form.

It also comprises the employment of raised 35 bosses forming screw head seats with depressed portions around said seats connected to the depressed edge portion of the hinge body which stiffen the body and at the same time form an extended bearing surface on 40 the face of the wooden door or other body to which the hinge is connected.

In the accompanying drawings Figure 1 is 45 a plan view of a hinge embodying the invention; Fig. 2 is an underside view of the same; Fig. 3 is a longitudinal section on the line 3—3 Fig. 2; Fig. 4 is a cross section on the line 4—4 Fig. 1; Fig. 5 is a cross section on the line 5—5 Fig. 1; Fig. 6 is a perspective 50 view of a portion of one hinge strap indicating the manner in which the metal is bent to form the knuckle; and Fig. 7 is an enlarged side view to more clearly bring out the construction.

55 My invention may be employed with any suitable form of hinge, either a butt hinge or

a strap hinge or a combination of the two. The drawing illustrates a combined butt and strap hinge in which 2 is the butt and 3 the strap, the butt having the two knuckles 4 and the strap the single knuckle 5, said 60 knuckles forming the barrel of the hinge through which the pintle 6 extends. The parts are made of relatively thin plate metal pressed to shape as illustrated to form a light strong hinge, the main plane of the 65 hinge body being indicated along its edges, for example at the edge portion 7 of the butt hinge extending from the knuckles 4 entirely around its edge and the portions 8 of the strap hinge extending from the knuckle 70 forward to the end screw hole 9. The flat edge 7 of the butt is connected with the flat portions 10 and the flat edge 8 of the strap is connected with the flat portions 11, so forming the broad bearing faces of the hinge 75 body upon the surface of the door or other part to which the hinge is connected. Between these surface bearing faces the metal of the hinge is pressed upwardly to impart strength to the hinge body. For example 80 this is shown in the butt at 12, where a continuous sinuous raised portion is provided, and in the raised portions 13, 14, in the strap, such raised portions imparting great stiffness to the two hinge members. The 85 screw seats 15 are formed in the depressed portions 10, 11, of the hinge, the metal being first forced upwardly to form the beveled screw bosses and thence downwardly to bring their bottom edges to the level of the 90 main body of the hinge member, and the bases 16 of these screw seats thus act with the depressed portions 10, 11, to give extended bearings on the surface to which the hinge is to be connected, increasing the 95 bearing surface in the same plane as the main body of the hinge member. In this way I am enabled to provide an ornamental hinge of light weight and great strength with a relatively large bearing surface especially disposed around the screw holes which prevents the metal at the screw holes from cutting into the wood body to which the hinge is connected; and in addition I provide 100 in the strap portions 11 depressed portion connected to the side edge portions 8 of the body, forming bearing surfaces for the hinge extending entirely across the strap at different points.

105 It is important to provide for a continuous 110

bearing of the hinge barrel on the pintle throughout the length of the knuckles of the members and also important to brace the knuckle portions and to stiffen the hinge body close to the barrel, as, especially in strap hinges, this part receives the greatest strain. This is provided for in the hinge embodying the invention in the following way: The raised portion 13 is carried within 5 the plane of the bend of the knuckle 5, and is extended to a point close to the pintle, such raised extension being shown at 17. The raised extension 17 is, however, narrowed somewhat, the body of the strap being 10 carried in at the lower plane on each side of the raised portion 17, as at 18-18, forming seats into which lugs 19 of the knuckle 5 enter and are seated, as well indicated in dotted lines in Fig. 6 and illustrated in Figs. 15 20 5 and 7. The end edge portion of the knuckle is provided with a recess 20 between the lugs 19, the bottom of which bears upon the raised extension 17 while the lugs 19 fit into the seats 18 on each side of said raised 25 extension. In this way a cylindrical knuckle of the same interior diameter throughout its length is provided having no projections which might cut into the body of the pintle 6, and the lugs 19 and raised extension 17 of 30 the body form a lock to sustain and include the parts 5 against displacement under strain, this very simple means bracing the part of the hinge on which the greatest strain is brought by a positive locking connection and supporting the turned over edge of the knuckle against vertical strain, immensely increasing 35 the strength of the hinge. The same construction is employed with the knuckles 4 of the butt hinge which are numbered in like 40 way but need no description. The metal forming the hinge members is pressed to shape, and the metal forming the knuckles is bent over into the cylindrical form, so providing square bearings at its edges of the full 45 width of the metal of the hinge body, for example, at 21, 21, so that the knuckles of the two members forming the barrel have square bearing surfaces upon each other well adapted to carry the load while the knuckles themselves are cylindrical throughout, and the 50 bracing obtained by the fitting of the raised extension 17 with its seats 18 at each side with the recesses 20 and the lugs 19 which enter within the bent portion of the knuckle 55 itself provides cylindrical knuckles of exceedingly strong construction adapted to carry heavy loads.

Practical use has proven that the hinge is

durable and of great strength while it can be made at relatively low cost. 60

What I claim is:

1. A hinge member having a cylindrical knuckle portion and a body portion having a raised extension forming part of the knuckle and a depressed seat at the side of the raised extension, the knuckle having a lug fitting in said seat. 65

2. A hinge member having a cylindrical knuckle portion and a body portion having a raised extension forming part of the knuckle, and depressed seats at the sides of the raised extension, the knuckle having a depressed seat fitting over said raised extension and lugs entering said depressed seats. 70

3. A pressed steel hinge member having 75 its main bearing surface along its edges, staggered screw seats extending above the bearing surface and depressed rings around the staggered screw seats forming bearing surfaces in the same plane as the main bearing surface and intermediate raised portions between the said depressed rings and the main edge portions of the hinge member, the intermediate raised portion adjacent the knuckle serving to support the knuckle 80 against longitudinal distortion. 85

4. A hinge member having a cylindrical knuckle portion and a body portion having a raised extension forming part of the knuckle and extending within the knuckle to reinforce the hinge, and depressed seats at the sides of the raised extension, the knuckle having a depressed seat fitting over said raised extension and lugs entering said depressed seats whereby the knuckle is supported against longitudinal distortion in 95 either direction. 90

5. A hinge, the members of which comprise cylindrical knuckle portions and body portions having raised surfaces extending 100 toward the knuckles, said raised surfaces having depressed seats at the sides thereof and said knuckles having recesses meshing with said raised surfaces and lugs adjacent 105 said recesses to engage in said seats, whereby said raised surfaces and said lugs mutually support each other against longitudinal distortion of the several knuckle portions.

In testimony whereof, I the said JAMES 110 P. McKINNEY have hereunto set my hand.

JAMES P. McKINNEY.
